UNITED STATES PATENT OFFICE

NORMAN FINLAY JOHNSTON, OF GLASGOW, SCOTLAND, ASSIGNOR OF ONE-HALF TO
JOHN ALEXANDER WILKIE, OF GLASGOW, SCOTLAND

BUILDING OR GARAGE FOR STOWING MOTOR CARS AND OTHER VEHICLES

Application filed October 15, 1928, Serial No. 312,697, and in Great Britain October 19, 1927.

In recent years, the rapid development of 5 motor traffic everywhere on the highways, roads and streets, is the chief cause of the present unsatisfactory state of the street traffic in general; and civic authorities have the difficult problem of how to handle, 10 garage or store the large and ever increasing number of motor cars, that nowadays encumber the roadways; that are a nuisance in themselves, a menace to other motor traffic, and often a danger to the general public; to provide reasonable garage accommodation in crowded areas.

The present invention relates to an improved system and building, to garage—in 15 congested areas—the maximum number of motor cars in the minimum space, at a minimum cost as regards to site, erection and type of building; and to provide a system 20 whereby motor cars can be quickly stored in a garage and quickly taken out of same, the operation being conducted without a possibility of damaging any car within a garage, and in the minimum of time. By 25 the arrangement, there is attained a simple and speedy method of handling motor cars within a garage, and ninety-six motor cars can be garaged within a fifty foot cube.

A garage constructed according to this invention, 30 consists of a multi-storey metal building; in construction, it is built substantially of metal columns, having H-section gallery floor beams, on which, angle bar, channel bar and T bar intermediate rails 35 support a checkered plate floor, the walls and roof are covered with plain or corrugated sheets.

On each side of the garage, in parallel, 40 a number of storeys are arranged in tiers, one over the other; the storeys are divided into rectangular stalls sufficiently large to accommodate a motor car; through the centre of the garage, and between the two parallel rows of rectangular stalls, a middle 45 corridor is arranged and formed in position; within the middle corridor, a movable traversing hoist is fitted, to operate on rails, whose platform is fitted with a rotary turntable.

50 The traversing hoist, consists of a shallow,

square travelling carriage, movable on rails provided on the ground at each side of the middle corridor, and fitted with a vertically movable hoist; the hoist platform is made of sufficient dimension to accommodate a rotary turntable, by means of which, motor cars can be turned at right angles to the middle corridor, and at right angles to the two parallel rows of rectangular stalls; the travelling carriage is open at the bottom, 55 thus permitting the cage of the hoist—when in the lowest position—to rest on the ground; the hoist cage is open through at the ends and sides, the ends, leading into the parallel rows of rectangular stalls, arranged 60 and erected on each side of the middle corridor, and the sides, leading into the middle corridor; to each side of the travelling carriage, a short runway is fitted.

The garage will thus be rectangular in 70 plan, having, arranged in parallel, two rows of multi-storey rectangular stalls formed at right angles to, and erected on each side of a middle corridor; the said corridor is arranged and placed in position through the 75 centre of the garage building, within which, a movable traversing hoist, fitted with a rotary turntable, is placed to operate and move on rails. All being arranged and combined, erected and contained under one 80 roof.

One construction of a garage building according to the present invention is illustrated in the accompanying drawing in which:—

Figure 1 shows, in outline, a plan of a garage, with a traversing hoist mounted on rails between two rows of rectangular stalls, arranged in parallel; the hoist platform is fitted with a rotary turntable, and the 90 traversing carriage, with four inclined runways.

Figure 2 is a vertical section of the same, showing detail of the building construction and the traversing hoist positioned in the 95 middle corridor.

In the construction shown in Figures 1 and 2, 1 is the garage building here divided into two multi-storey rows of rectangular stalls 2, each stall having an entrance into 100

the middle corridor 3, which is arranged and formed through the centre of the building; the rails 4, sunk level with the garage floor, are provided for the traversing carriage 5, 6 is the vertical hoist, 7 the four inclined runways fitted to the traversing carriage, 8 is the hoist platform, to which a rotary turntable 9, is fitted, 10 is the hoist cage.

- 10 In the detail construction shown in Figure 2, A is the upright vertical columns, which carry the gallery beams B; angle bars C, channel bars D, and T-bars E, constitute the intermediate rails which support 15 the floor plates F, on the gallery beams B; the wall sheets G, are fixed to the angle bars C, at end of the stalls. The vertical columns are set somewhat back in the middle corridor, to clear the runways 7, of the 20 travelling carriage 5; the gallery floors F, are extended out into the middle corridor 3, to meet the vertical hoist 6, and the overhang of the gallery floors F, are supported by the angle brackets H.
- 25 In the construction shown in Figures 1 and 2, a motor-car on entering the middle corridor of the garage, is driven up the inclined runway 7, across the vertical hoist platform 8, on to the rotary turntable 9.
- 30 With a concurrent movement the car is turned at right angles to the middle corridor 3, lifted vertically by the hoist 6, and moved in a horizontal direction by the 35 travelling carriage 5, in parallel with, and within the middle corridor 3, until the car arrives directly opposite to its stall; the car is then moved therein. Similarly when a 40 car is required, the traversing hoist 6, is brought opposite to the stall containing the car, the car is moved on to the rotary turntable 9, of the hoist 6, when, with a concurrent movement the car is turned at right angles to the parallel rows of stalls 2, and brought to the ground at any point within 45 the middle corridor 3, of the garage; the car will then have a clear run forward off the hoist, through the middle corridor, on, and out of the garage. The rails 4, in which the travelling carriage 5, move, are 50 sunk level with the garage floor, to enable the motor cars on the ground floor stalls 2, to have a clear run out of the garage, without having to pass through the traversing hoist. Motor cars are thus garaged in a 55 multi-storey building, having a middle corridor formed through the centre of the building, flanked on each side by rows of stalls in tiers, which are systematically served from, and by, the alternate ends of 60 a traversing hoist cage 10.

I am aware that it has been proposed to construct a garage on the outside of which there is fitted a travelling hoist disposed to operate and move on rails within a pit 65 which is placed outside and along the front

of the building, and also a garage having a vertically movable lift provided with a rotary turntable, giving access to each floor, any one or more of the floors being provided with rectangular or radially arranged compartments disposed around the central lift.

What is claimed is:—

In combination with a multi-story building having a longitudinal corridor extending throughout the height of the stories and lengthwise of the building and having rows of motor car receiving stalls in each story opening into the opposite sides of the corridor, a track extending lengthwise of the corridor on the ground floor of the building, a traversing carriage mounted on the track on the ground floor and having runways extending from the sides and ends thereof, and leading into the opposite ends of the corridor and into the adjacent opposed stalls, a hoist having a platform mounted on and carried by the carriage independently of the building structure, a turntable mounted on the hoist platform, 85 and a hoist cage on the platform enclosing the turntable.
